UNITED STATES PATENT OFFICE.

ALBERT BORCHARDT, OF HOBOKEN, NEW JERSEY, ASSIGNOR TO VICTOR HENRY ROTHSCHILD, OF SAME PLACE.

DESIGN FOR A SHIRT-BOSOM.

SPECIFICATION forming part of Design No. 19,171, dated June 25, 1889.

Application filed May 13, 1889. Serial No. 310,644. Term of patent 3½ years.

To all whom it may concern:

Be it known that I, ALBERT BORCHARDT, a citizen of the United States, residing at Hoboken, in the county of Hudson and State of New Jersey, have invented and produced a new and original Design for Shirt-Bosoms, of which the following is a specification, reference being had to the accompanying drawings, forming part thereof.

Figure 1 in the accompanying drawings represents a plan view of a shirt ornamented with my design, and Fig. 2 is an enlarged view of the essential feature of the design.

The essential feature of the design consists of a series of fanciful figures A, arranged one above the other, appearing to be united and representing an ornamental border. Each of the several figures A consists of two cord-like lines *a*, drawn in loop form, extending in opposite directions from a center circular figure *b*. A third cord-like line *d* in loop form is

represented as pendent from the center figure *b*, which latter loop figure appears to be inclosed by a diamond-shaped figure *e*, and at the opposite side corners of the diamond figure a small loop-like figure *h* is drawn, appearing to form a continuation of the said diamond figure. Between the border of figures A a knot-like figure *B* is drawn, and a large loop-like figure *C* is represented at each side of each end of the knot-like figure, having the appearance of being a portion thereof, and a button-like figure *E* is formed at the outer end of each of the large loop figures *C*.

I claim—

The design for shirt-bosoms, substantially as herein shown and described.

ALBERT BORCHARDT.
